CLAIM

The ornamental design for a shipping box insert, as shown and described.

DESCRIPTION

FIG. 1 is a top perspective view of a shipping box insert showing our new design.

FIG. 2 is a front view of the shipping box insert of FIG. 1. FIG. 3 is a rear view of the shipping box insert of FIG. 1. FIG. 4 is a left side view of the shipping box insert of FIG. 1.

FIG. 5 is a right side view of the shipping box insert of FIG. 1.

FIG. 6 is a top view of the shipping box insert of FIG. 1. FIG. 7 is a bottom view of the shipping box insert of FIG. 1; and,

FIG. 8 is a perspective view of the shipping box insert of FIG. 1 shown in a position of use with another exemplary shipping box insert and a shipping box.

The broken lines are shown for the purpose of illustrating environmental subject matter of an exemplary shipping box and exemplary shipping box insert and form no part of the claim.

1 Claim, 6 Drawing Sheets
